UNITED STATES PATENT OFFICE.

WILLIAM B. JAMES, OF LOS ANGELES, CALIFORNIA.

CONTAINER FOR TOILET CREAMS AND THE LIKE.

Application filed June 27, 1921. Serial No. 480,587.

To all whom it may concern:

Be it known that I, WILLIAM B. JAMES, a subject of the King of Great Britain, residing at Los Angeles, in the county of Los Angeles and State of California, have invented new and useful Improvements in Containers for Toilet Creams and the like, of which the following is a specification.

My invention relates generally to toilet articles, and more particularly to a holder for the collapsible metal tubes that are generally utilized as containers for toilet creams, dental paste, shaving cream and the like; the principal objects of my invention being to provide a relatively simple and convenient holder or container for the collapsible tubes, and which holder is of such structure as to enable it to be easily and cheaply produced; to provide a device that will receive and hold a collapsible tube and prevent the same from being crushed or broken when packed in a trunk or traveling bag; further, to combine with the device, means for gradually collapsing the tube to effect a discharge of the contents thereof; and further, to provide a collapsible tube holder that will receive and retain the collapsible tube in a convenient manner, and which may be placed in an upright position on a flat surface such as a table.

With the foregoing and other objects in view, my invention consists in certain novel features of construction and arrangement of parts that will be hereinafter more fully described and claimed, and illustrated in the accompanying drawings, in which:

Fig. 1 is a perspective view of the main body portion of a collapsible tube holder or container of my improved construction.

Fig. 2 is a perspective view of the removable base portion of the holder or container.

Fig. 3 is a perspective view of a collapsible metal tube that is adapted to be received by my improved holder or container.

Fig. 4 is a perspective view of the rotary member that is adapted to engage the collapsible tube for the purpose of folding or collapsing the same to effect a discharge of its contents.

Fig. 5 is a perspective view of my improved holder or container with a portion of one of the walls broken away and showing a collapsible tube positioned therein.

Fig. 6 is a perspective view of the holder or container with a collapsible tube positioned therein.

Fig. 7 is a vertical section taken approximately on the line 7—7 of Fig. 6.

The main body portion of the holder or container is preferably constructed from a suitable sheet metal that is presesed to form a substantially rectangular structure comprising side walls 10, end walls 11 and a cap or top plate 12, which latter is made slightly convex in cross section and being provided at its center with an aperture 13 of such size as to receive the threaded nipple or neck of a collapsible metal tube.

The end walls 11 are provided with vertically disposed slots 14, and, under normal conditions or before the holder is fitted with a collapsible tube, the resiliency of the metal of which the holder is formed tends to spread the lower portions of the side walls 10 apart.

The upper portions of the side walls 10 immediately below the cap or top plate 12 are pressed inwardly to form transversely disposed inwardly projecting ribs 15 and which latter are adapted to engage the upper portion of the collapsible tube that is positioned within the holder, thereby gripping said tube and firmly retaining it in proper position within the holder or container.

Adapted to be removably positioned on the lower end of the holder is a substantially rectangular securing cap 16 comprising side and end walls that are substantially L-shaped in cross section, and the end walls being indented or pressed inwardly as designated by 17 in order to enter the lower portions of the slots 14 in the end walls of the holder when the bottom cap is applied thereto, and to prevent accidental displacement or distortion.

The numeral 18 designates the body of a collapsible metal tube of the type generally used for containing toilet creams, dental paste and the like, the upper end of said tube being provided with a removable cap 19 and the lower portion of the body of said tube being folded over to form a substantially straight bead 20.

In order to gradually collapse or fold the body of the tube 18, I utilize a short shaft or stem 21 that is slotted as designated by 22 in order to receive the folded lower end portion 20 of the tube 18 and one end of said shaft or stem carrying a milled head or disc 23 whereby it may be readily engaged and rotated.

To properly arrange a collapsible tube within my improved holder, said tube is positioned within the holder with the cap 19 projecting through aperture 18, and after the 5 slotted stem or shaft 21 has been positioned on the folded lower end portion 20 of the tube with the milled head or disc projecting beyond one of the slots 14 in the holder, the lower ends of the side walls of said holder 10 are forced toward each other so that cap 16 may be positioned on the lower ends of the side and end walls of the body of the holder, and, as the side walls are thus moved toward each other, the inwardly projecting 15 ribs 15 will engage and press into the upper portion of the body 18 of the tube, thereby firmly clamping said tube and retaining it against vertical or lateral movement within the holder.

20 When it is desired to discharge a portion of the contents of the collapsible tube, cap 19 is unscrewed from the upper end of said tube, and by engaging the milled head or disc 23 and rotating the same and the stem 25 or shaft 21, a portion of the lower end of the collapsible tube will be wound upon said shaft or stem and consequently forcing a portion of the contents of the tube out through the nipple or threaded stem at the 30 upper end thereof.

A collapsible tube holder or container of my improved construction is comparatively simple, may be easily and cheaply produced, may be made in various sizes for the accommodation of different toilet articles that are 35 put up in collapsible tubes, and serves to prevent the contained tube from being crushed or broken when packed in a traveling bag or trunk.

It will be readily understood that minor 40 changes in the size, form and construction of the various parts of my improved collapsible tube holder or container may be made and substituted for those herein shown and described without departing from the spirit 45 of my invention, the scope of which is set forth in the appended claims.

I claim as my invention:

1. A container adapted to receive a collapsible tube and having at its top an aperture 50 through which the nipple of the tube may project, said container having also an interior, transverse, tube-retaining rib or bead near the top thereof and a longitudinally arranged slot, and also a removable securing cap adapted to cooperate with said slot to close one end of said container and to prevent accidental displacement or distortion, said slot being provided with a shaft 55 fitting rotatably therein and having an operating head, said shaft being slotted to receive the folded end of the collapsible tube.

2. A container formed of sheet metal and adapted to receive a collapsible tube and having an aperture in its upper end through 60 which the nipple of the tube may project and having vertical slots in opposite sides and an open lower end into which the slots extend, a shaft fitting in the slots and having a slot to receive the lower end of the collapsible tube, 70 and a cap fitting the lower end of the container and holding the shaft in place, said cap having indented portions to fit in the lower ends of the slots.

In testimony whereof I have signed my 75 name to this specification.

WILLIAM B. JAMES.
